ART HADLEY, OF PROVIDENCE, RHODE ISLAND, ASSIGNOR TO THE HADLEY COMPANY, INC., OF PROVIDENCE, RHODE ISLAND, A CORPORATION OF RHODE ISLAND

METHOD OF MAKING BRACELET LINKS

Application filed January 24, 1931. Serial No. 510,985.

This invention relates to flexible link bracelets of the type comprising a series of open-centered or hollow links and connecting members straddling the adjoining sides of adjacent links and more particularly to links plated with gold or other rare metal.

The usual practice of making link bracelets involves stamping the link units from sheet stock and then smoothing the edges and 10 polishing the surfaces. This procedure not only involves considerable waste of stock but it is wholly unsuited to plated stock for the reason that the peripheries of the stamped units would of course not be plated. Theoretically it would be possible to form links from bar stock plated on all sides but this would not be practical for the reason that the bending operations necessary to shape the links would deform the stock sufficiently to 20 require heavy swaging operations which would make the plating too thin in spots.

Objects of the present invention are to provide a bracelet construction in which plated stock may be used with little waste, without 25 exposing unplated surfaces and without any treatment after the bending operation which tends substantially to dislocate the plating.

To the attainment of this purpose I propose to make the improved link from a narrow bar or strip of plated sheet metal or flattened wire by cutting relatively small sections from one side of the strip and bending the strip upon itself to provide an open-centered link of rectangular or other appropriate 35 shape, with the ends of the metal substantially abutting each other at one side of the link. Several of such individual pieces may easily be cut from a single length of the material, and the forming operations may be 40 performed by hand or by suitable machinery at relatively slight expense and without substantially deforming any of the exposed surfaces of the links.

The accompanying drawings illustrate the 45 production of a recommended type of bracelet link in accordance with this invention, but it will be understood that the method and the resulting product may be varied in operation or design to suit particular purposes 50 without departing from the essence of my in-

vention as defined in the appended claims. In the drawings,

Fig. 1 is a perspective view of a metal strip or bar from which my improved link may be fabricated, the bar as a whole being indicated by full and broken lines and a strip suitably cut for the formation of a single link being shown by full lines;

Fig. 2 is a plan view of the bent-up link at an intermediate stage of its manufacture;

Fig. 3 is a plan view of the finished link;

Fig. 4 is a fragmentary plan view of a bracelet comprising a series of the links of Fig. 3; and

Fig. 5 is an enlarged section on line 5—5 of Fig. 4.

In the illustrated embodiment of my invention, the bar 6 consists of a single length of sheet metal or flattened wire stock of suitable character and flexibility. The stock is 70 generally rectangular in cross-section and is preferably smooth finished on its four sides. From this straight bar individual strips such as shown by the full lines of Fig. 1 are prepared by severing the bar transversely and 75 cutting away rectangular sections from one of its sides to provide longitudinally spaced recesses 7. The edges of the recessed portions of the strip may be left in a rough condition in order to save the expense of finishing the 80 cut surfaces, as indicated in the drawings; and it will be apparent that this practice will not impair the appearance of the finished link bracelet.

The strip thus prepared is next shaped to 85 the general contour of the ultimate link by bending the recessed or narrowed portions 8 and 8' thereof inwardly toward the rough sides of the spaced projections 9 formed by cutting the side recesses 7, the projections 90 serving, in effect, as mandrels about which the flexible portions of the metal strip are bent. Because of the projections 9 the corners of the resulting rectangle are deformed so little that 95 only a light swaging or rolling operation, if any, is required to flatten the corners. This operation also closes any gaps or seams which may appear at 10 between the wide ends 9 and the relatively narrow sides 8 of the link, and these seams are scarcely discernible in 100

the finished link in Fig. 3, appearing only as faint lines 13.

It will be observed that the projections 9 are formed at spaced intervals intermediate 5 the ends of the strip 6, and that the ends 8' of the strip are bent into abutting relation at one side of the link, as indicated at 11. It is also apparent that the unfinished surfaces of the blank 6 are observable only at the inner 10 edges of the side members of the completed link, between the smooth faces of the wide end portions 9.

These rough surfaces as well as the joint 11 (which may be soldered or welded if desired) are substantially concealed when the 15 links are assembled in a bracelet, for the wide intermediate connectors 12 (Figs. 4 and 5) customarily employed for this purpose surround the side members 8 of the interconnected links. In accordance with common 20 practice the connectors 12 may comprise a flat piece of metal bent over and encircling the adjoining sides of adjacent links of the bracelet, and in the present instance the 25 transverse dimension of the connector is preferably approximately equal to the corresponding dimension of the opening 14 in the link.

From the foregoing it is apparent that my 30 improved process consists essentially in the formation of an open-centered bracelet link shaped from a single length of metal by cutting longitudinally spaced, substantially rectangular recesses 7 from one side of the metal 35 strip to provide the projections 9 spaced from each other and from the ends of the strip, and by thence bending the strip transversely about said projections to bring its ends into opposed or abutting relationship, as at 11, and to carry 40 the narrow or side portions 8 and 8' into juxtaposition with the rough edges of the projections or wide ends 9. The further step of lightly rolling or swaging the surfaces of the link to flatten its corners and to close the 45 seams 13 at the corners of the central opening 14 (Fig. 3), while optional, is a desirable and recommended final step of the process and results in the production of a finished link of pleasing contour and appearance.

50 The completed link is thus extremely easy and economical to manufacture, yet it is substantially as durable in use and as attractive in appearance as a link fabricated by more expensive methods. As above explained, 55 when the links are interconnected by intermediate members surrounding their adjoining side portions, the rough edges and the joint between the abutting ends of the metal strip are effectively concealed, so that the 60 economical production of the bracelet is not apparent to the casual observer.

From the foregoing it will be evident 65 that this invention permits the use of plated stock without much waste, without exposing unplated edges and without dislocating or

unequally redistributing the plating material.

I claim:

1. A method of making a bracelet link which comprises cutting longitudinally spaced recesses in one side of a metal strip 70 to provide spaced projections disposed intermediate the ends of the strip, and bending the strip transversely about the said projections to bring the ends of the strip into opposed relation at one side of an open-centered 75 link.

2. A method of making a bracelet link which comprises cutting longitudinally spaced recesses in one side of a metal strip to 80 provide spaced projections disposed intermediate the ends of the strip, bending the strip transversely about the said projections to bring the ends of the strip into opposed relation at one side of an open-centered link, and swaging the surfaces of the link to flatten 85 the corners thereof.

3. A method of making a bracelet link from a straight strip of metal, which comprises cutting longitudinally spaced, substantially rectangular recesses in one side of the strip to provide a pair of similar rectangular projections spaced from each other and from the ends of the strip, and bending the strip transversely about said projections to bring its ends into abutting relation at one 95 side of an open-centered link with the side edges of the said projections juxtaposed to the inner surfaces of the side portions of the link.

4. A method of making a bracelet link from 10 a straight strip of metal, which comprises cutting longitudinally spaced, substantially rectangular recesses in one side of the strip to provide a pair of similar rectangular projections spaced from each other and from the 10 ends of the strip, and bending the strip transversely about said projections to bring its ends into abutting relation at one side of an open-centered link with the side edges of the 11 said projections juxtaposed to the inner surfaces of the side portions of the link, and rolling the surfaces of the link to flatten the corners thereof and close the seams between said juxtaposed surfaces.

Signed by me at Providence, Rhode Island, 11 this 10th day of December, 1930.

ART HADLEY.
